(57) **CLAIM**

I claim the ornamental design for the lamp, as shown.

DESCRIPTION

FIG. 1 is a perspective view of a lamp showing my new design

FIG. 2 is a front side elevational view thereof.

FIG. 3 is a back side elevational view thereof.

FIG. 4 is a right side elevational view thereof.

FIG. 5 is a left side elevational view thereof.

FIG. 6 is a top plan view thereof; and,

FIG. 7 is a bottom plan view thereof.

Any shading is not a feature of the design but is utilized to illustrate the surface contours of the lamp design in the drawings.

My lamp is characterized by the joining of right triangular forms of the same size from a side other than the hypotenuse in an upward direction.
